MAGNETRON

Herbert J. Reich, New Haven, Conn., assignor, by mesne assignments, to the United States of America as represented by the Secretary of the Navy

Application May 8, 1947, Serial No. 746,775

13 Claims. (Cl. 315—39)

1

The present invention relates to generators of ultra-high-frequency electromagnetic energy, and more particularly, the invention is concerned with tunable-resonator electron-discharge apparatus operable at frequencies of 10^9 or more cycles per second.

Ultra-high-frequency wave-energy generators are known which consist of a cylindrical cathode, a segmented or slotted anode coaxially disposed around the cathode, and a plurality of hollow cavity resonators connected to the anode at the slots therein. Electrons produced at the cathode are caused to gyrate or move spirally about the cathode in a cathode-anode interaction space by means of an axial magnetic field provided by a magnet whose poles are in axial alignment with the cathode and a radial electric field maintained between the cathode and anode. By proper selection of the voltage of the radial electric field and of the intensity of the axial magnetic field, the whirling electrons may be caused to yield energy to set up and reenforce standing electromagnetic waves in the resonators. Such generators, known in the art as cavity-resonator magnetrons, are efficient generators of electromagnetic energy at ultra-high frequencies largely determined by the fundamental frequency of the resonators as excited in a predetermined desired mode of oscillation.

Difficulty is encountered in the operation of such magnetrons where variation in operating frequency is desired or necessary. Known methods of controllably varying the operating frequency are productive of but small tuning ranges, and generally, even such small tuning ranges are accomplished at the expense of the overall Q of the apparatus with consequent reduction of the efficiency of the apparatus.

Accordingly, it is a principal object of the present invention to provide novel apparatus for generating ultra-high-frequency radio energy, particularly for frequencies of 10^9 or more cycles per second.

Another object is to provide novel ultra-high-frequency energy generator apparatus that is tunable over a relatively wide band of frequencies with substantially no alteration of the Q of the apparatus.

Still another object is to provide novel electrical and mechanical arrangements, including the structures as a whole, means for accomplishing adjustments of the high-frequency resonant circuits utilized therein, and means for the accomplishment of other desirable functions within the scope of the invention, including fre-

2

quency variation and stabilization, and other functional operations desirable in connection with the generation of high-frequency oscillations.

According to a preferred embodiment of the invention, wideband tuning of a magnetron is accomplished by providing a plurality of resonator devices in the form of adjustable-length, resonant sections of coaxial line, each of said resonant sections being individually adjustable, and means for conjointly adjusting the lengths of all the sections, whereby a range of tuning is provided for the magnetron that is substantially greater than that provided by prior-art magnetron generators.

Other objects and advantages will become apparent from the specification, taken in connection with the accompanying drawing wherein the invention is embodied in concrete form.

20 In the drawing:

Fig. 1 is a side elevational view, partly in cross-section, of a preferred embodiment of the invention,

Fig. 2 is a cross-sectional view taken along the line 2—2 of Fig. 1,

Fig. 2a is a fragmentary view illustrative of a detail of construction,

Fig. 3 is a transverse cross-sectional view illustrating a modified form of the invention,

Fig. 4 is a fragmentary elevational view, partly broken away, showing another modification, and

Fig. 5 is another fragmentary elevational view, partly broken away, illustrative of still another modified form of the invention.

35 Figs. 1 and 2 disclose a magnetron in accordance with the present invention. As shown, the magnetron comprises a cylindrical shell 11 which serves jointly as the evacuated envelope and anode of the magnetron and comprises a side wall 13 and end walls 15, 17. One end wall 17 is preferably removable to provide access to the interior of the shell 11 and, before evacuation, wall 17 may be secured in any suitable manner, as by silver soldering, to provide a vacuum-tight closure for the shell.

40 Coaxially mounted within the shell 11 is a conventional cathode assembly 19 consisting of an electron emitter 21 such as an activated oxide surface heated by a filament 23 (Fig. 2) which is, in turn, connected by means of leads 25 to a suitable source of driving and heating potential (not shown). The filament and cathode may be conductively connected for operation at the same direct potential.

45 For mounting resonators on the shell, the side

55

wall 13 is provided with a plurality of apertures equally spaced around the periphery of shell 11 and in a transverse plane midway between end walls 15, 17. Coaxial-line L-fittings 27 are mounted in the apertures, each said fitting comprising a tubular outer conductor 29 and an inner conductor rod 31 coaxially supported within the outer conductor 29 by means of dielectric beads or spacers 33. The fittings 27 are suitably secured in the wall 13, as by brazing or silver soldering, or any other suitable means for ensuring a vacuum-tight joint. The vacuum system is made complete by making the bead 33 nearer the wall 13 a vacuum seal, the parts of the apparatus beyond this bead being in communication with the atmosphere, if desired.

The inner end of the inner conductor 31 projects into the interior of shell 11 and may be terminated in a loop 35 for coupling to the electromagnetic field which may exist in the interaction space between cathode 19 and anode 13. Cooling may be effected in any desired manner, as by means of fins 36.

In the illustrative embodiment, there are shown eight apertures in the anode wall 13, seven of which are provided with L-fittings 27 as described. The eighth aperture is provided with a conventional coaxial line output terminal or antenna seal 31, for coupling the magnetron to a useful load. It will be understood that the number of L-fittings here disclosed is merely illustrative, any other suitable number may be employed.

Adjustable-length sections 39 of coaxial line are utilized as resonators and, as shown, the resonators are adapted to be detachably coupled to the L-fittings 27 by a conventional coupling-nut arrangement. As shown in Fig. 1, the adjustable-length resonator sections 39 are of identical construction, each being formed of a pair of telescopingly adjustable portions 41, 43 of coaxial line, said portions having outer conductors 45, 47 and inner conductors 49, 51, respectively. The outer conductor 47 is adapted to be received snugly within the outer conductor 45 while the inner conductor 49 is slightly tapered at one end to be telescopingly received within the inner conductor 51. The end of inner conductor 49 adjacent the L-fitting 27 is provided with an axial slot to receive the slightly tapered end of the inner conductor 31 of the L-fitting. As is well known, the inner conductor 45 may be suitably positioned coaxially of the outer conductor 45 by means of suitably positioned dielectric beads 33.

A short-circuiting conductive disc 53 is rigidly connected between inner conductor 51 and outer conductor 47 of resonator portion 43 so that, by adjustably varying the degree of insertion of portion 43 in resonator portion 41, the effective electrical length of resonator 39 may be altered. Generally, the effective electrical length is preliminarily adjusted to be substantially one-half wavelength at the desired operating frequency of the magnetron.

Each of the other L-fittings 27 are adapted to be provided with adjustable-length coaxial line resonators 39 similar to that described hereinabove. Only one other resonator 39 is shown in Fig. 1, the other adjustable-length coaxial line resonators having been omitted from the drawing in the interest of clarity of disclosure.

To provide for conjoint adjustment of the electrical lengths of resonators 39 there is provided an apertured interconnecting disc 55, through the holes of which the free ends of the

resonators 39 are adapted to be passed. Any suitable means may be used to provide for detachable mechanical connection of the resonators and the disc 55. For example, washers 57 may be secured adjacent the free ends of the portions 43 to provide shoulders on which the interconnecting disc 55 may rest. A series of aligned apertures 59 (Fig. 2a) may be formed in the outer conductor 47 of the portion 43 through which a pin 61 may be passed to secure the disc 55 in position. It will be noted that the series of aligned apertures are provided to make possible the addition of one or more additional removable washers of suitable thickness to compensate for inequality in the structural lengths of the coaxial line resonators 39 that may result from a preliminary independent adjustment of the electrical length of the individual resonators. A control rod 63 is centrally mounted on and secured to the disc 55, and may be provided with a knob 65 for manual adjustment of the disc 45, or, the rod 63 may be connected mechanically to any other suitable source of motive means for the purpose.

For providing a uniform magnetic field axially of the shell 11 a magnet, having pole pieces 67, is provided with the pole pieces disposed adjacent the end walls 15, 17 of the shell 11.

In operation, the cathode 19 is maintained at a suitable negative potential with respect to the grounded anode by means of a suitable source of direct potential (not shown). Electrons emitted from the cathode 19 are caused to move spirally thereabout and in the cathode-anode space as spoke-like "beams" under the joint influence of the radial electric field and the axial magnetic field. The effect of the rotating "beams" of electrons sweeping across the resonators 39 is to initiate and sustain ultra-high-frequency electromagnetic oscillations within the resonators in a manner similar to the production of ultra-high-frequency electromagnetic oscillations in the hollow cavity resonators of prior-known types of magnetrons. Accepted theories of the mechanism whereby this operation is achieved are set forth in an article by J. B. Fisk, H. D. Hagstrum and P. L. Hartman in The Bell System Technical Journal, vol. XXV, 1946, pages 169-221, to which reference is made for a fuller description.

As noted above, the frequency of oscillation of the magnetron is largely determined by fundamental frequency of the resonators, which, in turn, is determined by the effective electrical length thereof. Thus the lengths of the resonators may be independently and/or conjointly adjusted so that the electrical lengths are equal to one-half wave length at the desired operating frequency. It will be understood that electrical lengths corresponding to integral multiples of one-half wavelength may also be utilized.

The operating frequency of the magnetron is thus rendered easily variable over a wide range of frequency values. Such variations are accomplished by merely changing the effective lengths of the resonators by moving the interconnecting disc 55 in the appropriate direction.

Frequency modulation of the magnetron may also easily be accomplished, as by mechanically coupling the disc 55 to any suitable motive means for alternately increasing and decreasing the effective lengths of the resonators, as desired.

The ultra-high-frequency energy generated in the magnetron may be delivered to any useful load or utilization device by means of the coupling loop 75 37.

It will be understood that for ensuring the predominance of a desired mode of oscillation such conventional expedients as strapping or so-called "rising-sun" construction may be employed.

Fig. 3 illustrates, in diagrammatic form, a modified version of magnetron in which couplings to the interaction space are affected at points other than or in addition to those at which resonators may be located. Thus, instead of providing an output coupling loop in place of one of the coaxial line resonators, as in the form disclosed above, a full complement of L-fittings 27 is provided herein, each fitting being adapted to couple a coaxial line resonator (not shown) to the interaction space between cathode 19 and anode 13 of the type and in substantially the same manner as set forth above. One or more output couplings 61, 63 may be mounted with the loops thereof oriented in the interaction space so that the magnetic flux lines from the resonators thread therethrough in any desired amounts. In this manner it will be seen that multiple outputs are readily available.

To obtain greater uniformity of electromagnetic-field distribution relative to the cathode the modification shown in Fig. 4 is proposed. As shown, two circular arrays 71, 73 of resonator-coupling L-fittings are provided. Resonators (not shown) of the type described in connection with Figs. 1-2 are adapted to be coupled, as above, to respective ones of the L-fittings of each array. As shown in Fig. 4, the L-fittings of each array 71, 73 are disposed in concentric, axially-displaced circular arrangements with respective ones of the fittings 75 in array 71 in axial alignment with respective ones of the fittings 77 of the array 73.

The fittings 77 of array 73 are preferably formed with horizontally extending portions 79 sufficiently longer than the corresponding portions of fittings 75 of array 71 so that the axes of the resonators of each array, when assembled, are disposed along coaxial cylinders of unequal diameters. Conjoint variation of the electrical lengths of the resonators of each array may be accomplished by means of an interconnecting disc (not shown) in a manner similar to that shown above.

It will be seen that the dielectric spacer 33 that provides a vacuum seal between the shell wall 13 and the exterior may be positioned at the end of the L-fittings 75 and 77 inasmuch as the points of insertion of the L-fittings are adjacent to voltage nodes.

Output couplings 81, 83 for delivering the ultra-high-frequency energy generated in the magnetron to utilization devices are provided in a common transverse plane symmetrically disposed between arrays 71, 73, and, as shown, the couplings 81, 83 may be staggered between adjacent pairs of vertically-disposed resonators.

Fig. 5 shows a further modification of the invention, which while generally similar to the form illustrated in Fig. 3 insofar as the resonator arrangement is concerned, differing therefrom in that the output couplings 85, 87 are provided in a common plane displaced from the medial plane occupied by the fittings 27. In this form, the output couplings 85, 87 are preferably disposed in axial alignment with the resonators.

There has thus been described in the foregoing specification a magnetron generator wherein wideband tuning is accomplished by means of adjustable-length resonant sections of coaxial line, with each of the sections being independently adjustable and conjointly adjustable, as desired.

It is to be understood that various modifications and changes may be made in this invention without departing from the spirit and scope thereof as set forth in the appended claims.

I claim:

1. A high-frequency tube structure comprising means defining a substantially homogeneous cylindrical conductive shell adapted to contain a rotating electromagnetic field therewithin, cathode means disposed axially of said shell for producing a supply of electrons, means adjacent said shell for forming a plurality of beams of electrons rotating in synchronism with said field and defining paths substantially radial of said shell, and a plurality of short-circuited sections of coaxial transmission line extending outwardly from said shell and coupled in energy-interchanging relation with the interior of said shell, said sections of line forming the sole principal frequency-determining elements of the tube structure.

2. A high-frequency tube structure comprising means defining a substantially homogeneous cylindrical conductive shell, cathode means disposed axially of said shell for producing a supply of electrons, means adjacent said shell for forming a plurality of rotating beams of electrons defining paths substantially radial of said shell, a plurality of short-circuited sections of coaxial transmission line of adjustable length and extending outwardly from said shell and coupled in energy-interchanging relation with the interior of said shell, said sections forming the sole principal frequency-determining elements of the tube structure, and means for conjointly varying the lengths of said sections.

3. A high-frequency tube structure comprising a cylindrical shell, means for producing a rotating space charge of electrons extending substantially radially of said shell, a plurality of sections of coaxial transmission line disposed about and projecting radially from said shell, means in said shell for coupling said sections to said rotating space charge, whereby ultra-high-frequency electromagnetic fields are induced in said transmission line sections, and coaxial-line means connected to each said section for conjointly adjusting the lengths of said sections thereby to alter the frequency of oscillation of said ultra-high-frequency fields.

4. A high-frequency tube structure comprising a cylindrical shell, means for producing a rotating space charge of electrons extending substantially radially of said shell, a plurality of spaced arrays of coaxial transmission line sections, each said array comprising a plurality of coaxial line sections disposed about and projecting radially from said shell, the coaxial line sections of one array being in axial alignment with respective coaxial line sections of the other array, means in said shell coupling said sections to said rotating space charge whereby ultra-high-frequency electromagnetic fields are induced in said transmission-line sections, and short-circuited coaxial line means for conjointly adjusting the lengths of said sections thereby altering the frequency of oscillation of said ultra-high-frequency fields.

5. In apparatus of the kind described, means defining an electron beam oscillating field interaction space, means for producing a copious supply of electrons within said space, means for causing rotational motion of said electrons as a plurality of wheel-like spokes, a plurality of coaxial transmission line sections, each said section having respective ends thereof circumferentially

disposed in a common plane in said space and adapted to interact with said rotating electrons, adjustable means at the other end of each of said sections and including conjointly adjustable short-circuited sections of coaxial line telescopically fitted on each of said first-mentioned coaxial line sections for short-circuiting the coaxial lines, whereby each said section forms a resonator wherein standing electromagnetic waves of a predetermined frequency are initiated, and means interconnecting said adjustable means for conjointly varying the position of said short-circuiting means thereby to vary the frequency of said resonators.

6. An electron-discharge device comprising an anode consisting essentially of a cylindrical member having a plurality of openings in the wall thereof, a section of coaxial transmission line fitted in each said opening, said sections being of predetermined length to resonate at substantially the frequency of the ultra-high-frequency energy to be generated by said device and adapted to provide the sole principal frequency-determining elements of the device, a cathode within said member for supplying electrons within said cylindrical member, and means adjacent said cathode for providing a magnetic field within said member between said anode and cathode and to which said electrons are subjected.

7. An electron discharge device comprising an anode consisting essentially of a cylindrical member having a plurality of openings in the wall thereof, a section of coaxial transmission line fitted in each said opening, said sections being of predetermined length to resonate at substantially the frequency to be generated by said device, a cathode within said member for supplying electrons within said cylindrical member, means adjacent said cathode for providing a magnetic field within said member and between said anode and cathode and to which said electrons are subjected, and interconnecting said sections for simultaneously altering the predetermined lengths of said sections of coaxial line to render said sections resonant at another frequency thereby to alter the frequency of the energy generator by said device.

8. Electrical discharge device of the magnetron type, comprising an evacuated cylindrical conductive shell, means for producing a copious supply of electrons within said shell, means for causing rotational motion of said electrons, a plurality of independently adjustable coaxial transmission-line sections disposed to interact with said rotating electrons, thereby to set up a rotating electromagnetic field within said shell, each said section being dimensioned to form a resonator wherein standing electromagnetic waves of a predetermined frequency are set up, and multiple-channel means projecting into said shell and extending to the exterior thereof for conducting energy from said apparatus to a utilization device.

9. A high-frequency tube structure of the magnetron type, comprising a cylindrical anode shell, means supported axially of said shell for

producing rotating beams of electrons generally defining paths radial of said shell, spaced ultrahigh-frequency resonators extending radially and outwardly from said shell, said resonators comprising sections of coaxial transmission line, said sections being dimensioned for resonance at the operating frequency of said tube structure and forming the principal frequency-determining elements of the tube structure, and means for coupling said resonators with the interior of said shell.

10. The tube structure defined in claim 9 wherein said coupling means comprises inductive loops at the ends of said sections of transmission line, said loops being disposed within the reaction space in said shell and in mutual energy-coupling relation with said rotating beams.

11. A magnetron tube structure comprising a substantially hollow cylindrical anode, means partly within said anode for producing a rotating cloud of electrons extending substantially radially of said anode, a plurality of sections of coaxial transmission line dimensioned for resonance at the operating frequency of said tube structure and disposed about and projecting radially from said anode, said sections forming substantially the sole frequency-determining element of the tube structure, and means coupling said sections to said rotating electron cloud, whereby ultra-high-frequency electromagnetic fields are induced in said transmission line sections.

12. The tube structure as claimed in claim 11 wherein said coupling means comprises inductive loops at the ends of said sections of transmission line and disposed within the reaction space in said anode, said loops being at voltage nodes of the oscillating fields in said sections.

13. In a high-frequency magnetron device, having a cylindrical anode surface and a plurality of coaxial-line resonators projecting radially therefrom, and in which the anode surface and the resonators are intercoupled by a rotating high-frequency electromagnetic field in a region adjacent the resonators, extensions on said coaxial-line resonators, said extensions being arranged in mutually parallel relation and parallel to the axis of said anode surface, movable tuning means in said extensions and including adjustable short-circuited sections of coaxial transmission line telescopically fitted in each said coaxial line resonators, and means for conjointly moving said short-circuited sections.
